Frank S. Balfett *Joseph B. Campbell*

UNITED STATES PATENT OFFICE.

JACOB B. CAMPBELL, OF YONKERS, NEW YORK, ASSIGNOR TO WILLIAM JAMES HOGG, OF WORCESTER, MASSACIUSETTS.

DESIGN FOR CARPET.

SPECIFICATION forming part of Design No. 25,225, dated March 3, 1896.

Application filed December 16, 1895. Serial No. 572,374. Term of patent 3 $\frac{1}{2}$ years.

To all whom it may concern:

Be it known that I, JACOB B. CAMPBELL, a citizen of the United States, residing at Yonkers, in the county of Westchester and State of New York, have invented and produced a new and original Design for Carpets, of which the following is a specification.

My invention relates to a design to be worked into or upon carpeting or other similar fabric; and I do hereby declare that the drawing accompanying this specification gives and conveys to any one skilled in the art of carpet-weaving a clear understanding of the same that is sufficient to enable such person to use my invention.

The said drawing is a face view of a carpet embodying my design.

The drawing illustrates a body and a border.

The body A consists of a substantially uniform groundwork upon which appear flowers resembling daisies having long interlacing stems with a few leaves growing from them. These are all arranged in an apparently careless manner.

The border B consists of a substantially uniform

groundwork upon which appear figures conforming in character to those in the body A. The inner margin is defined by a straight band finished at the top with a scalloped edge and broken at regular intervals by a small set figure. The outer margin is characterized by bands having an irregular or zigzag outline, upon which appear at intervals small sprigs of leaves.

The colors employed for the different portions of this design may be varied to suit the convenience or taste of the manufacturer.

What I claim, and desire to secure by Letters Patent, is—

1. In a design for carpeting, the body A, substantially as shown.
2. In a design for carpeting, the border B, substantially as shown.
3. The design for carpets, consisting of the body A and the border B, substantially as shown.

JACOB B. CAMPBELL.
